UNITED STATES PATENT OFFICE.

ALBERT E. MAYNARD, OF SOUTHBIDGE, MASSACHUSETTS, ASSIGNOR TO AMERICAN OPTICAL COMPANY, OF SOUTHBIDGE, MASSACHUSETTS, A VOLUNTARY ASSOCIATION OF MASSACHUSETTS.

EDGING MACHINE.

Application filed December 26, 1924. Serial No. 758,120.

This invention relates broadly to edging machines, and more particularly to an edging machine for grinding the edges of rimless or bevelled lenses.

5 A most important object of my invention is the provision of an edging machine having a plurality of grinding stones, together with means for contacting a lens with any one grinding stone, the grinding stones being adapted to grind the edges of different types of lenses.

A still further object of my invention is to provide a machine of unitary structure on which an operator may accomplish processes 15 usually requiring at least two machines, said processes including the edging of ophthalmic lenses of a plurality of shapes, and for either bevelled or rimless types.

Still another object of my invention is the 20 provision of an edging machine having a pair of edging stones, one of said edging stones having a V-shaped grinding edge and being flexibly mounted to adapt itself torsionally to the contour of a lens of any 25 shape, the other of said grinding stones having a straight grinding edge rigidly mounted and having means for laterally reciprocating the same in order to prevent its uneven wearing.

30 A further object of my invention is the provision of an edging machine having a lens holding carriage and means for shifting the lens holding carriage laterally to position a lens into grinding contact with any 35 one of the grinding stones, together with means for revolving the lens while in contact with any one of the grinding stones.

Still another object of my invention is to 40 provide a machine of this character with a pair of guiding elements, each of said guiding elements being independently adjustable, and a plurality of formers, means for arranging the formers to bring any one into operative relation with either of the guiding 45 elements, and a plurality of guiding edges carried by the guiding elements in order to accommodate any one of a number of different sizes of lenses.

50 Other objects and advantages of my invention will become apparent during the

course of the following description taken in connection with the accompanying drawings, wherein—

Figure 1 is a front elevation of a machine constructed according to my invention; 55

Figure 2 is a top plan view of the same showing a lens positioned before the straight edged grinding stone;

Figure 3 is a top plan view of the same showing a lens in position before the V- 60 shaped grinding stone;

Figure 4 is a detailed sectional view taken on line 4—4 of Figure 3, and showing the specific structure of the grinding stones;

Figure 5 is a detailed perspective view of 65 the means for shifting the former relative to the guiding elements; and

Figure 6 is a detailed sectional view showing the locking mechanism for holding the former in adjusted position. 70

Figure 7 is an end elevation from the right in Figure 1 with casing broken away to show the structure of the formers.

In so far as I am aware it has in the past been necessary for retailing opticians to 75 have in their shops at least two edging machines, one for edging rimless lenses, and the other for edging bevelled lenses, due mainly to the fact that although there have been machines constructed to accomplish 80 these two grinding processes, there has never been a machine of this type constructed without certain undesirable features.

It is, therefore, an important object of 85 my invention to provide, in a grinding machine, structure including the following, which will make possible a unitary machine for accomplishing these two grinding processes; structure overcoming these difficulties includes two grinding elements, one being 90 rigidly mounted on its driving shaft but having a flexible connection between its V-shaped grinding edge and rigid connection in order that it may yieldingly adapt itself to the contour of the lens, the other grinding 95 stone being rigid throughout its body, but being slidably mounted on its driving shaft, and having means for laterally reciprocating it to prevent the uneven wearing along its 100 grinding edge. Next, two independently

adjustable guiding elements, each element comprising a plurality of guiding shoes, and means for selectively using any one of the guiding shoes on either of the guiding elements. These independently adjustable guiding elements make possible individual adjustment for each of the grinding stones, such that a single guiding element can be set for a single grinding stone and its adjustment changed merely as it becomes necessary to compensate for the wearing of its respective grinding stone.

Further, a plurality of formers, including all standard shapes enclosed in a single casting, means to slide the casing into juxtaposition with either one of the guiding elements, and means to revolve all of the formers as a unit to bring any one group, and subsequently any one former, in operative engagement with the desired guide shoe. Then finally, a lens carriage which can be adjusted laterally to present a lens to either of the grinding stones.

An added feature of my invention becomes apparent when the machine constructed in accordance therewith is used for the exclusive grinding of bevelled edges. Heretofore it has been necessary in grinding bevelled edges, especially on lenses which are slightly over size, to either first grind the lens to size on a straight edge grinding machine, then remove the same and apply the bevel on a bevel edging machine, or else accomplish the whole operation on an ordinary bevel edging machine, which had its disadvantages in the length of time required to grind the lens to size. An ordinary bevel edging machine, if it must first grind a lens to size before edging the same, requires from eight to ten minutes to accomplish the operation, while if it becomes necessary to remove the lens from a straight edge grinding machine on which it has been ground to size and then center the same in a bevel edge grinding machine in order to grind the bevel, there is not only a waste of time in changing the lens from one machine to the other, but there is also always the possibility of not positioning the lens the same in both machines, and thus ruining the same by grinding it slightly off center.

My machine, however, eliminates all the difficulty incident to this, in that it is possible to take an over size lens and grind the same to size on the straight edge grinding stone, and then without removing the lens from the machine, shift the carriage to position the lens before the bevel edge grinding stone, and then apply the bevel, thus saving from six to eight minutes in the operation.

This feature becomes particularly important in a shop where a number of lenses are to be bevelled, and time becomes an impor-

tant factor, as it makes possible the edging of between three and four times as many lenses in the average day.

Referring now particularly to the drawings, wherein I have shown the preferred embodiment of my invention, the numeral 10 designates the base of my improved machine, the same being provided with the bearings 11, through which rotates the shaft 12 extended at one end to receive a pulley 13, by which power is applied to the shaft 12 and subsequently to the entire machine. Mounted between the bearings 11 and keyed to the shaft 12 are two grinding stones 14 and 15. The grinding stone 14 comprises a V-shaped peripheral grinding edge 16 carried by an annular stone section 17 flexibly joined by means of a flexible connection 18 to a solid hub 19, rigidly mounted on the shaft 12 by means of a key such as 20. The grind-stone 15 is of the usual construction, being provided with a straight edge 21 but being slidably keyed to the shaft 12 by means of a sleeve 22 slotted as at 23 to receive the pin 24 carried by the shaft 12. Integral with the outer end of the sleeve 22 is a collar 25 having on its periphery a cam groove 26 in which rides a guiding pin 27 rigidly mounted in the frame of the machine, whereby the collar 25, the sleeve 22, and grinding stone 15 are all caused to reciprocate laterally as the shaft 12 is revolved. Supported by, but to one side of, the base 10, and by means of the ear 28, are a pair of guide ways 29, in which are slidably mounted guiding elements 30 independently adjustable by means of the thumb screws 31, and the threaded shanks 32. The guiding elements 30 comprise knurled blocks provided with a plurality of guiding edges 33 revolvably mounted on the pivot pins 34, whereby they may be independently rotated to bring any one of the guiding edges 33 into operative position. Mounted forwardly of the shaft 12 and parallel thereto is a second shaft 35 driven by the shaft 12 through suitable gearing enclosed in a shell and designated broadly by the numeral 36, a universally jointed shaft 37 and a pair of spiral gears 39 and 40 respectively. The shaft 35 is provided adjacent its opposite end with an elongated gear 41, and at its end with a clutch mechanism 42. Pivotally mounted on the shaft 35 and slidably thereon is a lens carriage 43 provided with a downwardly projecting pin 45^a. A suitable lever 43^a, pivoted in the base 10, as at 44^a, has one end slotted as at 46^a to receive the pin 45^a, thus furnishing means for laterally shifting the lens carriage, while a weight 47^a mounted on the top of the lens carriage tends to swing the same about its pivot and force it toward the edging stones. Mounted on the top of the lens carriage 43 are a pair of opposed aligned lens

clamping shafts 44 and 45 adapted to clamp between their opposed ends a lens 55^A. The shaft 44 is slidably and rotatably mounted in a suitable bearing 46, and is normally forced toward the shaft 45 by means of a spring pressed arm 47, operating through a cross yoke 48 pivoted as at 49, and encircling the shaft 44 as at 50. A lever 51 pivoted in the carriage 43 by means of a suitable pivot 52 is pivotally fastened to the arm 47 by a pin 53 and is used to slide the shaft 44 against the force of the spring 54.

The shaft 45 is not slidable relative to the lens carriage, but is rotatable therein, being driven through a large gear 55 driven from the gear 41 on the shaft 35 through an idler 56. The shaft 45 is extended beyond the gear 55 to form the reduced portion 57, on which is mounted the gear 58, and a revolvable casing 59. The casing 59 is provided with a plurality of stub shafts 60 upon each of which are mounted a plurality of formers 61 and integral therewith gears 62 meshing with the gear 55 and adapted to rotate each of the formers in unison with the lens 55^A being edged and rotated by the shafts 44 and 45. The casing 59 is further provided with a lateral sleeve extension 63 formed on the end of which is a knob 64 by which the entire casing, including all of the formers, may be revolved to bring any one of the formers into operative position.

A spring pressed key 64^A locks the casing into any desired position. An annular supporting band 65 surrounds the casing 59 and is extended downwardly to form the arm 66, loosely encircling the shaft 35 and extending below the shaft to form a stub 67 provided with the longitudinally extending arcuate groove 68. Mounted on the side of the base 10, and directly beneath the stub 67 is a plate 69, which is substantially fan shaped, provided adjacent its wider end with a series of holes 70. Pivotally mounted on the plate 69 by means of a pivot 71 is a lever 72 provided at one end with a pin 73 adapted to ride in the groove 68 of the stub 67. The opposite end of the lever is provided with a spring pressed pin 74 adapted to engage any one of the holes 70, but provided with a pin 75 projecting from one side for locking the pin in retracted position by engagement with a bayonet slot 76 formed in a casing 77 surrounding the pin 74. By turning the lever 72 about its pivot 71 and locking the same in any one of its several possible positions by means of the pin 74 in the holes 70, the former casing 59 may be shifted along the shaft 57 and any one of the formers 61 aligned with any one of the guiding edges 33.

From the foregoing description it will become apparent that I have provided a machine which is capable of grinding in a thorough and efficient manner, lenses of different sizes and of many shapes, regardless of whether they be rimless or bevelled. In operating my machine it is only necessary to depress the lever 51, thus separating the two shafts 44 and 45, center a lens therebetween, and then permit the spring 54 to return the shafts 44 and 45 to normal position, thus clamping the lens. Power applied to the shaft 12 by means of the pulley 13 revolves the two grinding stones 14 and 15 and is subsequently furnished to the shaft 35 by means of the flexible shaft 37 and the gearing 36, 39 and 40. From the shaft 35 power is obtained for the lens holding shafts 44 and 45 by means of the idler gear 56 and the large gear 55, and the lens 55^A is revolved while in contact with either of the stones 14 or 15. The lever 43^A is used to shift the carriage 43 so that the lens may be contacted with either of the grinding stones and the lever 72 to shift the former casing 59 relative to the guiding elements 30 so that any one of the formers 61 may be placed in contact with any desired guiding edge 33. In practice it has been found advisable to adjust one guiding element for each of the grinding stones and leave the same in that adjustment, varying it only as the grinding stone becomes worn. In this way compensation can be made for the uneven wearing of the two grinding stones. The collar 25 carrying the cam groove 26 laterally reciprocates the stone 15, thus preventing the uneven wearing of its grinding edge, and the flexible connection in the grind stone 14 permits the stone 14 to yieldingly follow the shape of the lenses and makes possible the accurate beveling of lenses of any shape.

While I have shown and described but one form of my invention, it is by no means the only form which my invention may take, inasmuch as I reserve the right to make certain departures herefrom in so far as I remain within the spirit of the invention and the scope of the appended claims.

Having thus described my invention, I claim:

1. An edging machine, comprising a frame, a pair of guiding shoes carried by the frame, a grindstone shaft journaled in said frame, a pair of grindstones mounted on said shaft, one of said grindstones being provided with a V-shaped grinding edge, the other grindstone being provided with a straight grinding edge, means for axially reciprocating said last mentioned grindstone during rotation with respect to the shaft on which it is mounted, a second shaft parallel to the grindstone shaft and driven thereby, a lens carriage pivotally mounted on the second shaft, means for shifting the lens carriage out of the grinding range of one grindstone into grinding range of the other grind- 130

stone axially of the second shaft, a third shaft parallel to the second shaft and carried by said lens carriage and driven by said second shaft, a former slidably mounted on said third shaft, and means for sliding said former on the third shaft to align it with either of the said guide shoes.

2. An edging machine comprising a frame, a pair of guide shoes carried thereby and a 10 grindstone shaft journaled therein, a grindstone for edging beveled lenses and comprising a V-shaped grinding edge and mounted on said shaft, another grindstone for edging rimless lenses and comprising a 15 straight grinding edge and slidably mounted on said shaft, means for laterally reciprocating said last mentioned grindstone on its shaft, said means comprising a laterally extending sleeve carrying said grindstone and 20 surrounding said shaft, a collar mounted on the outer end of said sleeve, and a pin carried by the frame for engaging a cam groove formed in the collar, a second shaft parallel to the grindstone shaft and driven thereby, 25 a lens carriage pivotally mounted on the second shaft, means for shifting the lens carriage out of the grinding range of one grindstone into grinding range of the other grindstone axially of the second shaft, a third 30 shaft parallel to the second shaft carried by said lens carriage and driven by said second shaft, a former slidably mounted on said third shaft, and means for sliding said former on the third shaft to align it with 35 either of the said guide shoes.

3. An edging machine comprising a frame, a pair of guide shoes carried thereby and a grindstone shaft journaled therein, a grindstone for edging beveled lenses and comprising a 40 V-shaped grinding edge and mounted on said shaft, another grindstone for edging rimless lenses and comprising a straight grinding edge and slidably mounted on said shaft, means for laterally reciprocating said 45 last mentioned grindstone on its shaft, said means comprising a laterally extending sleeve carrying said grindstone and surrounding said shaft, a collar mounted on the outer end of said sleeve, a pin carried by the 50 frame for engaging a cam groove formed in the collar, a second shaft parallel to the grindstone shaft and driven thereby, a lens carriage pivotally mounted on the second shaft, means for shifting the lens carriage 55 out of the grinding range of one grindstone into grinding range of the other grindstone

axially of the second shaft, a third shaft parallel to the second shaft carried by said lens carriage and driven by said second shaft, a former slidably mounted on said third shaft, and means for sliding said former on the third shaft to align it with either of the said guide shoes, said means comprising a plate 60 formed at one side of the frame and having a series of perforations formed adjacent the outer edge thereof, a lever pivotally mounted on said plate, a pin carried by one end of said lever for shifting said former, and a spring pressed locking pin carried by the opposite end of said lever for locking engagement with any one of the series of perforations.

4. A lens edging machine for rimming and bevelling lenses comprising a frame, a 65 grindstone shaft, means for rotating the shaft, a grindstone rigidly mounted on the shaft, a second grindstone slidably mounted on the shaft, means for reciprocating the 70 slideable grindstone as it rotates with the shaft, a pivotally mounted and sliding lens 75 carriage adapted to hold the lens in grinding contact with either grindstone, a movable former associated with the lens carriage for regulating the shape of the lens as it is ground by either grindstone, a guide shoe 80 contact for the former for each of the grindstones, means to slide the lens carriage to engage the lens with either grindstone, and means to slide the former to engage either 85 of the guide shoe contacts to govern the shape 90 of the lens being operated upon by the corresponding grindstone.

5. A lens edging machine for rimming and bevelling lenses comprising a frame, a 95 grindstone shaft, means for rotating the shaft, a grindstone having a straight edge mounted on the shaft, a second grindstone having a V-shaped groove in its edge mounted on the shaft, a pivotally mounted and 100 slideable lens carriage adapted to hold the lens in grinding contact with either grindstone, a movable former associated with the lens carriage for regulating the shape of the lens as it is ground by either grindstone, a guide shoe contact for the former for each 105 of the grindstones, means to slide the lens carriage to engage the lens with either grindstone, and means to slide the former to engage either of the guide shoe contacts to govern the shape of the lens being operated 110 upon by the corresponding grindstone.

ALBERT E. MAYNARD.
